UNITED STATES PATENT OFFICE.

ARTHUR SWENSON, OF MANOR, TEXAS.

RAIL-JOINT.

No. 909,346.

Specification of Letters Patent.

Patented Jan. 12, 1909.

Application filed May 21, 1908. Serial No. 434,126.

To all whom it may concern:

Be it known that I, ARTHUR SWENSON, a citizen of the United States, residing at Manor, in the county of Travis and State of Texas, have invented certain new and useful Improvements in Rail-Joints, of which the following is a specification, reference being had to the accompanying drawings.

My invention relates to improvements in joints for track rails and its object is to provide the meeting ends of two rails with a simple and practical scarf or interlocking connection which will effectually hold them in perfect alinement, and at the same time permit them to be readily disconnected.

With the above and other objects in view, the invention consists of the novel features of construction and the combination and arrangement of parts hereinafter fully described and claimed, and illustrated in the accompanying drawings, in which—

Figure 1 is a side elevation of my improved rail joint; Fig. 2 is a vertical transverse section taken on the irregular plane indicated by the line 2—2 in Fig. 1; Figs. 3 and 4 are perspective views of the ends of the track rails; and Fig. 5 is a detail view of the locking key or wedge.

In the drawings 1 and 2 denote the adjacent ends of two track rails of the usual T-shape or design which have their ends connected and interlocked by my improved scarf joint and which may be secured upon cross ties 3 in the usual manner by spikes 4.

In constructing my improved joint I cut away a portion of the end of the web of the rail 1 so as to leave the base flanges projecting and in this projecting portion 5 I form a centrally disposed longitudinally extending slot or opening 6. I also cut away a portion of the head of the rail 1 so as to leave a portion 7 of the web projecting and I further round or bevel the upper end 8 of said projecting portion 7 of the web. The other track rail 2 has its abutting end shaped to engage the end of the rail 1 and this is accomplished by cutting away the base flanges of the rail 2 so as to receive the projecting portion 5 of the base flanges of the rail 1. The recessing or cutting away of the base flanges of the rail 2 leaves the web portion of the same projecting and upon the bottom of this projecting portion 9 of the web is formed a depending lug or projection 10 adapted to enter the slot 6 in the rail 1 and to have its lower end

project beneath the bottom faces of the base flanges of the rail 1.

In the projecting lower end of the lug 10 is formed a transverse slot or opening 11 to receive a locking key or wedge 12, as presently explained. The outer end of the projecting portion 9 of the web of the rail 2 is cut away to provide a projecting portion or end 13 upon the head of said rail, said portion 13 being adapted to project over the projecting portion 7 of the web of the rail 1 and being formed in its bottom face with a recess 14 shaped to receive the upper end 8 of said portion 7. By shaping the meeting ends of the rails 1, 2 as shown and described, it will be seen that the rail 2 may be readily engaged with the rail 1 by placing its projecting portion over the recessed portion of the rail 1 and dropping the lug 10 into the slot 6, and that when the rails are thus engaged they will be held in perfect alinement and against longitudinal or transverse shifting movement. The key 12 serves to hold the ends of the rail against vertical movement with respect to each other and is in the form of a long tapered or wedge-shaped plate adapted to be driven transversely through the slot or opening 11 in the lug 10 and to engage the bottom face of the projecting portions 6 of the base flanges of the rail 1. When driven into the slot or opening 11 it effectively draws the overlapping ends of the rails together and may be secured in position by bending its small end 15 upwardly around the outer edge of the portion 6 of the rail 1, as shown more clearly in Fig. 2.

Having thus described my invention what I claim is:

1. A rail joint comprising two rails, one having its head and web portions cut away to provide a projecting base flange portion, the latter being formed with a central opening, the other rail having its web and base flange portions cut away, the projecting web portion being provided with a depending lug to project through the opening in the base portion of the other rail, the projecting lower portion of the lug being formed with a transverse opening, and a key arranged in the latter to retain the lug in its opening.

2. A rail joint comprising two rails, one having its head and web portions cut away to provide a projecting base flange portion, the latter being formed with a central opening, the other rail having its web and base

flange portions cut away, the projecting web portion being provided with a depending lug to project through the opening in the base portion of the other rail, the projecting lower end of the lug being formed with a transverse opening, and a transverse wedge - shaped locking key passed through the opening in said lug and having its ends bent to engage the edge of the base of the rail to retain it in the lug.

3. In a rail joint, the combination of two track rails, one having its head and web portions cut away to provide a projecting web portion, the latter having its upper end rounded or beveled and the projecting base flange portion being formed with a centrally arranged opening, the other rail having its web and base flange portions cut away to pro-

vide a projecting web portion and a projecting head portion, the latter being formed in its under face with a recess to receive the upper end of the projecting web portion on the first mentioned rail, the bottom of the projecting web portion of the second mentioned rail being formed with a depending lug to pass through the opening in the base flange portion of the first mentioned rail and having in its projecting end a transverse opening, and a locking key passed transversely through the opening in the lug.

In testimony whereof I hereunto affix my signature in the presence of two witnesses.

ARTHUR SWENSON.
